UNITED STATES PATENT OFFICE

132,888

DESIGN FOR A PIN OR SIMILAR ARTICLE

Viola Both, Maspeth, Long Island, N. Y.

Application May 13, 1942, Serial No. 106,888

Term of patent 7 years

To all whom it may concern:

Be it known that Viola Both, a citizen of the United States of America, residing at Maspeth, Long Island, in the county of Queens and State of New York, has invented a new, original, and ornamental Design for a Pin or Similar Article, of which the following is a specification, reference being had to the accompanying drawing, forming part thereof.

Fig. 1 is a front view of a pin or similar article embodying my new design.

Fig. 2 is a top plan view thereof.

I claim:

The ornamental design for a pin or similar article, as shown.

VIOLA BOTH.
